UNITED STATES PATENT OFFICE.

MICHAEL BECK, OF MINNEAPOLIS, MINNESOTA.

CARBURETING APPARATUS FOR EXPLOSIVE-ENGINES.

1,029,740.

Specification of Letters Patent. Patented June 18, 1912.

Application filed November 20, 1911. Serial No. 661,368.

To all whom it may concern:

Be it known that I, MICHAEL BECK, a citizen of the United States, residing at Minneapolis, in the county of Hennepin and

5 State of Minnesota, have invented certain new and useful Improvements in Carbureting Apparatus for Explosive-Engines; and I do hereby declare the following to be a full, clear, and exact description of the invention, such as will enable others skilled 10 in the art to which it appertains to make and use the same.

My invention has for its object to provide an improved carbureting apparatus for use 15 in connection with explosive engines, and is especially adapted for use in connection with explosive engines of automobiles.

More specifically stated, the invention provides means whereby the vapor of gasolene 20 or relatively light hydro-carbon liquid, or the vapor of kerosene or a relatively heavy liquid hydro-carbon, is automatically rendered available in the explosive engine. For instance, in starting the engine, the 25 gasolene vapor is available and the exhaust from the engine is used to assist in vaporizing the kerosene, so that the kerosene vapor is used chiefly in running the engine. If however, there should be a failure at any 30 time to properly generate the vapor from the kerosene, the vapor from the gasolene will be automatically supplied to keep the engine going until there is again a proper generation of the vapor from the kerosene.

35 In the accompanying drawings which illustrate the invention, like characters indicate like parts throughout the several views.

Referring to the drawings, Figure 1 is a 40 plan view showing the running gear of an automobile, and showing my improved vaporizing apparatus connected to the explosive engine thereof; Fig. 2 is a detail showing the so-called primary oil heater chiefly 45 in longitudinal vertical section with some parts in full; Fig. 3 is a view partly in plan and partly in horizontal section showing the so-called secondary oil heater, some parts being broken away; Fig. 4 is a detail in vertical section approximately on the line $x^4 x^4$ on Fig. 1, showing the automatic valve mechanism for controlling the supply of the one or the other of the two kinds of vapor; Fig. 5 is a front elevation of the 55 parts shown in Fig. 3, some parts being sectioned and some parts being broken away;

Fig. 6 is a detail in section on the line $x^6 x^6$ on Fig. 3; and Fig. 7 is a detail showing the delivery end section of the kerosene or heavy oil supply pipe.

60

Of the parts of the automobile, the numeral 1 indicates the running gear frame, the numeral 2 the front wheels, the numeral 3 the rear wheels, and the numeral 4 the multicylinder explosive engine which is 65 equipped with an ordinary or suitable carbureter 5, and is provided with an exhaust pipe 6. In accordance with my invention, the exhaust pipe 6 is connected to one end of the casing 7 of a so-called primary oil heater, 70 and the other end of this casing 7 is shown as connected by a short pipe 8 to the casing 9 of a so-called secondary oil heater. The said casings 7 and 9 are both supported by and suitably secured to the frame 1. The 75 exhaust pipe 8, at the point where it leads into the casing 9, is provided with a pivoted damper or valve 10, and beyond this point, the said exhaust pipe 8 is connected to a final exhaust pipe 11, that preferably terminates at the rear portion of the running gear. This so-called final exhaust pipe 11 is provided with a branch 11^a that opens into the casing 9 of the secondary heater. The 80 damper 10 is shown as provided with a stem 12 by means of which it may be moved so as to cut off the exhaust pipe 8 from the casing 9, and thereby prevent the exhaust from entering the said casing, or said damper may be set, as shown in Fig. 3, so as to permit 85 part of the exhaust to enter the said casing 9.

The kerosene or heavy oil is contained in a supply tank 13 and the gasolene is contained in a supply tank 14. Both of these tanks, as 90 shown, are connected together and suitably supported by the frame 1 or other suitable part of the machine. Both of said tanks 13 and 14 are connected to the casing of a so-called controller valve. As shown, this casing of the said controller valve is made up 95 of a cup-shaped section 15 having a detachable pipe 17. The lower portion of the gasolene tank 14 is connected by a small pipe 18 to a valve seat 19 formed at the lower end of the cup 15, while the kerosene supply pipe 20 extends from the lower portion of the tank 13 and is connected to a nipple 21 on the upper portion of the pipe 17. The said kerosene supply pipe 20 includes a manifold coil 20^a that is contained 100 within the casing 7 of the primary oil heater, and it preferably also includes a coil 20^b 105

105

110

contained within the casing 9 of the so-called secondary oil heater. Also, the said kerosene supply pipe 20 extends through the exhaust pipe 8. Preferably, the coil 20^a is made up of pipe sections that increase in diameter in the direction in which the oil is fed therethrough, so as to thereby give increasing conducting capacity for the oil, or oil and vapor as they are expanded by the application of heat from the exhaust. Preferably, the delivery end of the pipe 20 is formed with an inverted U-shaped section 20^c having a small spring-closed check valve 20^d in its crown. The purpose of this 15 crook pipe section 20^c and valve 20^d is to prevent a siphon action from being started in case oil should be splashed violently within the tube. The crown of the crooked pipe section 20^c should be slightly higher than 20 the top of the oil supply tank 13. If oil should be splashed and caused to fill the section 20^c, the suction produced by the weight thereof would open the valve 20^d and thus break the siphon action. Preferably, the delivery end portion of the kerosene pipe 20 is connected to the gasolene pipe 18 by a small branch pipe 27 having a valve 28, by means of which it may be 25 opened and closed, at will. Ordinarily, the valve 28 will be closed, but it may be opened when it is desired to mix gasolene and kerosene vapors for delivery to the carbureter 5. In cold condition, the two gases will not readily mix, but when well heated, 30 they are adapted to be commingled in the explosive mixture. Normally, the valve seat 19 is closed by a ball valve 22 which is gravity-seated, and is provided with a depending finger 23 located within the valve seat 19 and serves to prevent the ball from being 35 displaced, and assists in guiding the said ball back to its proper seat. By reference to Fig. 4, it will be noted that there is an annular passage 24 formed between the cup 40 15 and pipe 17 of the valve casing, and that this annular passage is connected to a vapor conducting pipe 25 which is suitably connected to the carbureter 5 of the engine. Preferably, the valve casing 15-17 is covered 45 with an asbestos or similar heat insulating jacket 26.

The kerosene and gasolene supply tanks 13 and 14 are both closed, being, as shown, provided with removable caps 13^a and 14^a, 50 respectively, for filling purposes. When the engine is at rest, or before it has been run long enough to thoroughly heat the kerosene and generate gas therefrom, there will be no pressure within the casing 15-17 of the controller valve, and hence, the valve 22 will be only lightly seated by gravity. Hence, when starting the engine, the suction from the engine will raise the valve 22 and draw gasolene to the carbureter. After the 55 engine has been run a short time, the heat

from the exhaust will generate a gas from the kerosene or heavier hydro-carbon, and the pressure of this generated gas will assist in holding the valve 22 seated, and the carbureter of the engine will then be supplied only with the vapor from the kerosene or heavy oil. 70

If at any time there should be a failure in the proper supply of oil from the kerosene, the valve 22 will be lifted and the gasolene vapor will be supplied to the carbureter until the proper supply of vapor from the kerosene is again generated. Sometimes, or under certain conditions, the exhaust action on the coil 20^a in the primary heater, will be sufficient to properly generate the gas from the heavy oil, but when this is not sufficient, the exhaust is also directed through the casing 9 of the so-called secondary oil heater and thus additional heat 80 is furnished for generating gas from the heavy oil. 85

Kerosene and gasolene are the hydro-carbon oils which will, probably, usually be employed, but the broad idea of the invention 90 is to provide a carbureting apparatus in which, in the main, or chiefly, heavy and comparatively cheap oils may be used to run the engine, but which, for starting and for emergency, or when necessary, a lighter 95 hydro-carbon oil is available.

What I claim is:

1. The combination with an explosive engine, of an automatic controller valve, two tanks for containing relatively light and heavy liquid hydrocarbons, means for vaporizing said heavy hydrocarbon, a conduit connecting the tank containing the lighter hydrocarbon to said valve, a conduit extending from the tank containing the 100 heavy hydrocarbon to said valve, and a conduit connecting said valve to the said engine, said valve being arranged for cutting off the supply of lighter hydrocarbon, when the heavier hydrocarbon is vaporized to create 105 a sufficient pressure on said valve to keep it closed.

2. The combination with an explosive engine having an extended exhaust conduit, of an automatic controller valve, two tanks for 110 containing relatively light and heavy liquid hydrocarbons, means for vaporizing said heavy hydrocarbon, a conduit connecting the tank containing the lighter hydrocarbon to the said valve, a pipe extending from the 115 tank containing the heavy hydrocarbon, through said exhaust conduit to the said valve, and a pipe connecting said valve to said engine, said valve being arranged for cutting off the supply of lighter hydrocarbon, when the heavier hydrocarbon is vaporized to create 120 a sufficient pressure on said valve to keep it closed.

3. The combination with an explosive engine having an extended exhaust conduit, 125

of an automatic controller valve, two tanks for containing relatively light and heavy liquid hydrocarbons, means for vaporizing said heavy hydrocarbon, a conduit connecting the tank containing the lighter hydrocarbon to said valve, a pipe extending from the tank containing the heavy hydrocarbon, through said exhaust conduit to the said valve, a pipe connecting said valve to said engine, said valve being arranged for cutting off the supply of lighter hydrocarbon when the heavier hydrocarbon is vaporized to create a sufficient pressure on said valve to keep it closed, and a valved conduit connecting the said conduit for relatively light vapor to the conduit pipe for the relatively heavy vapor, substantially as described.

4. The combination with an explosive engine, of a tank for a liquid hydrocarbon, and a conduit connecting said tank to said engine, having an inverted U-shaped intermediate section provided with an air inlet valve in its crown kept closed under a light pressure, said crown being located at a point above said tank, substantially as described.

5. The combination with an explosive engine having an extended exhaust conduit, of a tank for a liquid hydrocarbon, and a conduit connecting said tank to said engine, including a coil or manifold located in said

exhaust conduit, the said conduit having an inverted U-shaped intermediate section provided with an air inlet valve in its crown kept closed under a light pressure, said crown being located at a point above the said tank, substantially as described.

6. The combination with an explosive engine having an extended exhaust conduit, of an automatic controller valve, two tanks for containing relatively light and heavy liquid hydrocarbons, means for vaporizing said heavy hydrocarbon, a conduit connecting the tank containing the lighter hydrocarbon to the said valve, a conduit extended from the tank containing the heavy hydrocarbon, through said exhaust conduit to the said valve and having an increased cross section in the direction in which the liquid hydrocarbon is delivered therethrough, and a conduit connecting said valve to said engine, said valve arranged for cutting off the supply of lighter hydrocarbon when the heavier hydrocarbon is vaporized to create a sufficient pressure on said valve to keep it closed, substantially as described.

MICHAEL BECK.
